(57) **CLAIM**

The ornamental design for a cover apparatus, as shown and described.

DESCRIPTION

FIG. 1 is an upper right frontal perspective view of the cover apparatus;

FIG. 2 is a lower left frontal perspective view of the cover apparatus;

FIG. 3 is a front elevational view of the cover apparatus;

FIG. 4 is a left side elevational view of the cover apparatus;

FIG. 5 is a right side elevational view of the cover apparatus;

FIG. 6 is a rear elevational view of the cover apparatus;

FIG. 7 is a top plan view of the cover apparatus;

FIG. 8 is a bottom plan view of the cover apparatus;

FIG. 9 is an upper right frontal exploded perspective view of the cover apparatus; and,

FIG. 10 is a lower left frontal exploded perspective view of the cover apparatus.

The dashed lines are for the purpose of illustrating environmental subject matter that forms no part of the claimed design.

1 Claim, 8 Drawing Sheets
